(57) **CLAIM**

The ornamental design for a ticket scanner, as shown and described.

DESCRIPTION

FIG. 1 is a perspective view of a ticket scanner in accordance with the present design;

FIG. 2 is a left side elevation thereof;

FIG. 3 is a front elevation thereof;

FIG. 4 is a rear elevation view thereof;

FIG. 5 is a top plan thereof; and,

FIG. 6 is a perspective view thereof in which a stanchion and base are illustrated using phantom lines to indicate an example environment.

The broken lines in the figures show portions of the ticket scanner which form no part of the claimed design, or show aspects of an example environment that form no part of the claimed design.

1 Claim, 3 Drawing Sheets
